UNITED STATES PATENT OFFICE.

ROBERT L. COLLARD, OF DERMOTT, ARKANSAS.

SLIDING-DOOR FASTENER.

1,120,373.

Specification of Letters Patent.

Patented Dec. 8, 1914.

Application filed February 26, 1914. Serial No. 821,253.

To all whom it may concern:

Be it known that I, ROBERT L. COLLARD, a citizen of the United States, residing at Dermott, in the county of Chicot and State 5 of Arkansas, have invented certain new and useful Improvements in Sliding-Door Fasteners, of which the following is a specification, reference being had to the accompanying drawings.

10 This invention relates to new and useful improvements in car doors and more particularly to an improved fastener therefor, the main object of the invention being the provision of a fastener which is particularly 15 adapted to sliding car doors and is so arranged that the door cannot be locked until the same is in an entirely closed position.

A still further object of the invention is the provision of a sliding door fastener 20 which will possess advantages in points of efficiency and durability, is inexpensive to manufacture and, at the same time, is simple in construction and operation.

With the above and other objects in view, 25 the invention consists in the novel features of construction, combination and arrangement of parts as will be hereinafter referred to and more particularly pointed out in the specification and claims.

30 In the accompanying drawing forming a part of this application, Figure 1 is a front elevation of a car door constructed in accordance with my invention. Fig. 2 is a longitudinal sectional view taken upon the 35 line 2—2, Fig. 1. Fig. 3 is a top plan view of the movable locking bar. Fig. 4 is a transverse sectional view taken on the line 4—4, Fig. 1; and Fig. 5 is a transverse sectional view of the locking bar.

40 Referring more particularly to the drawings, the numeral 8 designates a car door and disposed in a vertical position, are the stop rails 9 and 10, the rail 9 being arranged along one of the longitudinal side edges of 45 the door opening 2, while the rail 10 is arranged at a point removed from the opposite or longitudinal side edge of the opening, and at a distance which is substantially the same as the width of the door and is 50 adapted to limit the sliding movement of the door when the same is opened. In order to retain the door against swinging movement when the same is moved to open position, I provide a retaining plate 11, one end 55 of which is rigidly secured to the car and stop rail, while the other end thereof pro-

jects beyond the inner face of the stop rail 10 and engages over the outer face of the door.

The top 5 when in its closed position is rigidly retained against any sliding or swinging movement by means of a rotary catch member which is generally indicated by the numeral 13 and which is substantially rectangular in form, having one of its side 60 edges thereof rounded, as shown at 14 to permit rotation of the same, without engaging with the car body. The ends of the locking member 13 are provided with spindles 15 suitably mounted within bearings 70 16, arranged upon opposite sides of the door opening at the lower end thereof, whereby said locking member may be readily rotated to engage or disengage the same over the lower end of the door. One side of the 75 locking member is provided with a longitudinal recess 17 which forms an engaging flange 18 which, when the locking member is in its locked position, engages over the lower edge of the door to securely hold the 80 same against outward swinging movement. The closed ends of the recesses, which are indicated by the numeral 19 retain the door against any sliding movement whatsoever.

The locking member is provided at one 85 end with a cutaway portion, as shown at 20 which provides a shoulder 21, with which the catch 22 is adapted to engage to prevent rotary movement of the locking member. The locking plate 23, upon which the catch 90 member 22 is formed, includes a metal plate, one end of which is bent upon itself to form a loop adapted to engage over one of the spindles 15, said plate projecting 95 outwardly and having its other end disposed at right angles and provided with an opening 24. The looped end of the plate extends upwardly beyond the catch 22 to reinforce said catch member, as indicated in Fig. 4. Secured to the car body and arranged at the lower end of the stop member 9, is a plate 25 having formed thereon the outwardly projecting perforated ears 26 in which is slidably mounted a locking bolt 27, the lower end of said bolt being adapted 100 to engage within the opening 24 to retain the locking plate 23 in its effective position so that the catch member 22 will engage the shoulder 21 and hold the locking member 14 against rotation.

110 From the above, it will be apparent that the door member 5 will be securely held

against any sliding or swinging movement when in its locked position. In Fig. 1 the door is shown in its locked position and in order to unlock the same, it is only necessary 5 to remove the bolt 27, releasing the plate 28 and swinging the same outwardly so that the locking member 14 can be rotated to release the door. The door may then be swung outwardly by grasping the handle member 10. 28 or the same may be readily slid upon the track rail 3, to an open position, the stop rail 10 limiting the sliding movement of the door.

It will be apparent from the foregoing description that I have provided a simple and durable car door which is mounted for sliding and swinging movement whereby should the contents of the car become jammed against the door during transportation, the door 20 may be readily opened, without injuring the same or the fastening means, which support the door, or without tearing the door from its fasteners. It will also be apparent that the door cannot be locked in its effective position, until the same is entirely closed, thus preventing the slatting or nailing of the door in a partly closed position. It will be apparent that my improved car door and fastening means may be quickly and readily 30 applied to any of the well known forms of freight cars now in use and, at the same time, is simple in construction and can be manufactured at a comparatively low cost.

While I have shown and described the 35 preferred form of my invention, it will be obvious that various changes in the details of construction and in the proportions may be resorted to for successfully carrying my invention into practice, without sacrificing 40 any of the novel features or departing from the scope of the appended claims.

Having thus described this invention, what I claim is:—

1. A device of the class described including a door mounted for sliding movement, a

rotary locking member provided with a longitudinal recess, a flange formed continuous with the recess and adapted to engage over the lower edge of the door, the ends of said recess being closed to prevent lateral movement of the door when the locking member is in its effective position, and means for retaining said locking member in its effective position. 50

2. A device of the class described including a car door mounted for sliding movement, a locking member mounted for rotary movement and having a longitudinal recess formed therein, a flange formed continuous with the recess and adapted to engage over the lower edge of the car door, said recess having its ends closed to prevent lateral movement of the door, one end of said locking member having a recess providing a shoulder, a pivotally mounted locking plate 65 having a catch adapted to engage said shoulder when the locking member is in its effective position, and means for retaining said catch in engagement with the shoulder. 60

3. A device of the class described including a car door mounted for sliding movement, a rotary locking member having a longitudinal recess in one end thereof providing an engaging flange adapted to engage the lower edge of the door, flanges 70 formed upon each end of said locking member, one end of said locking member having a recess forming a shoulder, a locking plate rotatably mounted upon one of said flanges and having a catch adapted to engage said shoulder when the plate is in its locked position, and means engaging one end of the plate to retain the same in its effective position. 75

In testimony whereof I hereunto affix my 80 signature in the presence of two witnesses.

ROBERT L. COLLARD.
